UNITED STATES PATENT OFFICE.

FRANK W. SKINNER, OF TAFT, CALIFORNIA.

GAS BURNER.

Application filed October 10, 1921. Serial No. 506,599.

To all whom it may concern:

Be it known that I, FRANK W. SKINNER, a citizen of the United States, residing at Taft, in the county of Kern and State of California, have invented new and useful Improvements in Gas Burners, of which the following is a specification.

This invention relates to gas burners and is particularly directed to a burner especially 10 adaptable for firing furnaces.

The objects of the invention are, to provide a burner having a burner tube in which the gas supply is directed in hollow cone formation across the area of the tube so that all 15 the air entrained through the tube to form with the gas a combustible mixture must pass through the gas cone; to provide means independently varying the amount of air entrained through the tube; to provide means 20 independently varying the volume of the gas cone; and to provide means for combining steam with the gas before it enters the tube.

Various other objects and advantages will 25 be more fully apparent from the following description of the accompanying drawings which form a part of this disclosure, and which illustrate a preferred form of embodiment of the invention.

30 Of the drawings:

Fig. 1 is a vertical section through a portion of a furnace with my improved type of burner installed therein.

Fig. 2 is an enlarged section through the 35 rear portion of the burner.

Fig. 3 is a section on line x^3-x^3 of Fig. 2.

In the preferable method of installation as 40 illustrated in Figure 1 the burner projects downwardly at an angle through an opening in the furnace wall with its axis in line with a baffle wall extending across the floor of the furnace, there being no air admitted through the opening through which the burner projects.

45 The burner comprises a burner tube 1 and a burner head 2 screw-threaded on the outer end of the tube, said head having a gas nozzle 3 projecting axially into the tube and centrally bored to accommodate the fuel control mechanism. The burner head 2 is provided with a plurality of circularly spaced air inlet ports 4 and rotatable on the head is a sleeve valve member 5 having a like number of openings and constituting a 50 means by which the air admitted to the burner may be independently controlled. A

set screw 6 carried by the sleeve 5 engages the head 2 and serves as a means for retaining the sleeve in adjusted position.

The forward edge of the gas nozzle is 60 tapered outwardly to form an angled valve seat 7 and cooperating with said seat is a valve 8 of cone formation, the seat and valve cooperating to form an annular fuel orifice angled to direct the fuel into the burner tube 65 in hollow cone formation and against the side walls of the tube so that all the air entrained through the air inlet ports 4 must pass through such gas cone.

The valve 8 is carried by a valve stem 9 70 which extends rearwardly through a plug 10 screw-threaded into the burner head and through a stuffing box 11. The stem has a screw-thread engagement with the plug 10 and by turning the stem by the handle 12 the 75 valve 8 may be translated to vary the volume of the fuel fed into the burner tube.

An inner tube 13 surrounding the valve stem, is screw-threaded into the plug 10 and projects forwardly to a point just rearwardly of the fuel valve 8 and a steam supply pipe 14 is screw-threaded into the side of the plug 10 and is in communication with the inner tube 13. A gas supply pipe 15 is screw-threaded into the side of the burner 85 head 2 and communicates with the bore of the fuel nozzle 3.

In the operation of the burner the gas under pressure is fed from the fuel nozzle 3 in the form of a hollow cone directed 90 forwardly and towards the walls of the burner tube. By this arrangement all of the air which is combined with the fuel in the burner must pass through the fuel cone thereby causing a very intimate mixture of 95 the fuel and air.

This, in effect, produces a thin partition of fuel across the entire area of the tube with the air passing through such fuel partition in a manner by which the maximum 100 area of the fuel molecules will be exposed to intimate contact by the air in its passage through the fuel partition.

Such arrangement results in a perfect mixture contributing to maximum burner 105 efficiency.

In some instances it is desirable to combine a certain amount of steam with the fuel and to meet such conditions the burner is provided with the inner tube 13 by which 110 steam is conducted to the nozzle and combined with the fuel.

It is not intended to confine the invention to the one form of embodiment herein illustrated and described, for it is susceptible of embodiment in various other forms all coming within the scope of the claims which follow.

I claim:

1. A gas burner comprising a fuel nozzle tube having an annular seat at its forward end and a closure at its rear end, a cone valve cooperating with said seat to form an annular fuel orifice, a valve stem connected to the apex of the valve and having a screw-threaded engagement with the closure of the tube and extended therethrough for manual manipulation, a fuel inlet for the tube, a steam tube surrounding and spaced from the rod and projecting within the nozzle tube past the fuel inlet to a point adjacent the cone valve, said steam tube having an open forward end for discharging steam directly along the rod and against the valve surface to thoroughly scour the rod and valve surface, and a steam inlet for the steam tube.

2. In a gas burner, a burner tube having an air inlet, a fuel nozzle axially aligned

with and extending into the tube beyond the air inlet with its forward end formed to provide an annular valve seat, a cone valve 30 cooperating with said seat to form an annular fuel orifice directing a hollow cone shaped column of fuel towards the tube walls, a fitting closing the rear end of the nozzle and having a steam inlet, a valve 35 actuating rod secured to the apex end of the cone valve and having a screw thread engagement in said fitting rearwardly of the steam inlet, and a steam pipe carried by said fitting and axially projecting into the nozzle to a point adjacent the cone valve, said pipe surrounding and spaced from the rod and having an open inner end discharging steam directly along the rod and against the valve surface to 45 thoroughly scour the rod and valve surface, the rod being entirely supported by said fitting.

Signed at Taft, California, this 29th day of September 1921.

FRANK W. SKINNER.
